United States Patent Office

Des. 222,537
Patented Nov. 2, 1971

222,537

SEAT

Marilyn Lewis, Beverly Hills, Calif., assignor to Hamburger Hamlets, Inc.

Filed Dec. 15, 1969, Ser. No. 20,495

Term of patent 14 years

Int. Cl. D6—01

U.S. Cl. D15—8

FIG. 1

FIG. 2

FIG. 1 is a perspective view of a seat constructed according to principles of this invention; and

FIG. 2 is a side view of the seat taken from the left of FIG. 1;

The article is the same in appearance when viewed in perspective from an angle directly opposite that of FIG. 1.

I claim:

The ornamental design for a seat, as shown and described.
